PAPER FOLDING APPARATUS

Application filed February 27, 1930. Serial No. 431,776.

In fanfolding paper such as used in certain bookkeeping or record keeping systems, it has been customary to first perforate the web of paper on the lines on which the fold is to be made and to subsequently crease the paper on these lines by separate mechanism to cause the paper to fold in the desired directions after it leaves the creasing mechanism.

I find, however, that due to stretching of the paper it is very difficult to keep the creasing in alinement with the perforating, no matter how carefully the apparatus is operated, and therefore the paper does not always fold properly.

My object therefore, is to devise means whereby the perforating and creasing on each line a fold is to be made may be done simultaneously so that both the perforating and creasing will always be in alinement.

I attain my object by means of the constructions hereinafter described and illustrated in the accompanying drawings in which

Fig. 1 is a more or less diagrammatic view showing one form of apparatus for carrying out my invention;

Fig. 2, a similar view showing a modified form of apparatus;

Fig. 3, an enlarged sectional detail of the female member of the perforating and creasing mechanism; and

Fig. 4, an enlarged sectional detail of the male member.

In the drawings, like numerals of reference indicate corresponding parts in the different figures.

Referring to Fig. 1, 1 indicates a roll on which is positioned the web of paper 2 which is to be fanfolded. From this roll the paper is led between two contacting rolls 3.

Each of the rolls 3 is provided at diametrical points with a female member 4 and a male member 5, the male member 5 on the one roll being arranged to co-act with the female member on the other roll.

The female members 4 are each provided with a groove 6 extending longitudinally of the roll, and the male members 5 are each provided with a series of perforating pro-

jections 7 arranged longitudinally of the roll. The grooves 6 are, for a purpose which will hereinafter appear, somewhat wider than the perforating projections 7.

As shown in Fig. 3, the female members 4 which are set into the surface of the rolls 3 are formed in two parts, each having a recess in their contacting faces in which is received a bar 8 of fibre or similar material, the bar of fibre forming the bottom of the groove 6. Damage to the perforating projections 7 is therefore avoided as the fibre bar will give under the action of the perforating projections.

The male members, which are also set into the rolls 3 are formed in two sections, 9 and 10, the sections being clamped together by screws 11 to hold the toothed projections in position.

The operation of the apparatus above described is as follows. The paper is drawn from the roll 1 and is fed between the rolls 3, where the male members 5 first force the paper into the grooves 6 in the members 4, and then perforate the paper on spaced lines by pressure against the bottom of the groove, at the same time causing a creasing or folding of the paper which tends to further break the fibres of the paper. As the members 4 and 5 are arranged alternately on opposite rolls, it will be evident that the perforating and creasing will be done alternately on opposite sides of the paper and consequently the paper as it leaves the rolls 3 will tend to fold alternately in opposite directions to secure the proper fanfold arrangement.

In Fig. 2 an alternative arrangement is shown in which the paper is fed between rollers 13. The female members 4 are arranged one at one side of the paper and one at the other, the male members being arranged at the opposite side of the paper to the female members. Means will be devised for alternately moving one member of each pair. With this construction the paper will be fed forward intermittently, the steps being equal to double the distance between folds and the set of co-operating members 4-5 will be arranged apart a distance equal to the distance between the folds.

In the drawings, I show the upper members 4 and 5 as mounted on a vertically moving frame 14, which may be operated in any suitable manner, as for example, by a lever 15 which is operated by a cam 16 mounted on a shaft 17.

From the above description it will be seen that I have devised apparatus which will satisfactorily attain the object of my invention 10 as set out in this specification.

What I claim as my invention is:

1. In paper folding apparatus, the combination of a pair of creasing and perforating members arranged one at each side of the path along which paper is to pass whereby the paper is creased and perforated from opposite sides, said creasing and perforating members being positioned relative to one another so that the creases and perforations 15 made by one member are alternated with those made by the other member, and grooved members co-operating with and into which said creasing and perforating members project to crease the paper along the lines of 20 perforations, the bottoms of said grooves forming supporting surfaces for the paper while the perforating is being effected.

2. In paper folding apparatus, the combination of a pair of rolls, each having in its surface a line of creasing and perforating projections, the projections on one roll being positioned relative to those on the other roll to alternately crease and perforate from opposite sides paper passing between said rolls, 30 each of said rolls having a groove in its surface adapted to co-operate with the creasing and perforating projections on the other roll to crease the paper along the lines of perforation, the bottoms of said grooves forming 35 supporting surfaces for the paper while the perforating is being effected.

3. In paper folding apparatus, the combination of a pair of perforating members arranged one at each side of the path along 45 which paper is to pass whereby the paper is perforated from opposite sides, said perforating members being positioned relative to one another so that the perforations made by one member are alternated with those made by the other member, and grooved members 50 co-operating with and into which said perforating members project to crease the paper along the lines of perforations, said grooved members comprising a pair of metal members having recesses 55 in their adjacent faces, a strip of softer material fitted in said recess, said metal members being spaced apart at one side to form a groove of which the strip of softer material forms the bottom.

60 4. In paper folding apparatus, the combination of a pair of creasing and perforating members arranged one at each side of the path along which paper is to pass whereby the paper is creased and perforated from 65 opposite sides, said creasing and perforating

members being positioned relative to one another so that the creases and perforations made by one member are alternated with those made by the other member, and grooved members co-operating with and into which said creasing and perforating members project to crease the paper along the lines of perforations, the bottoms of said grooves forming supporting surfaces for the paper while the perforating is being effected, 70 each groove being of a width sufficient to receive a creasing and perforating member and a double thickness of the paper to be operated upon.

5. In paper folding apparatus, the combination of a pair of rolls, each having in its surface a line of creasing and perforating projections, the projections on one roll being positioned relative to those on the other roll to alternately crease and perforate from opposite sides paper passing between said rolls, 80 each of said rolls having a groove in its surface adapted to co-operate with the creasing and perforating projections on the other roll to crease the paper along the lines of perforation, the bottoms of said grooves forming 85 supporting surfaces for the paper while the perforating is being effected, each groove being of a width sufficient to receive a creasing and perforating member and a double 90 thickness of the paper to be operated upon.

6. In paper folding apparatus, the combination of a perforating member arranged at one side of the path along which paper is to pass, and a grooved member co-operating with and into which said perforating member projects to crease the paper along the line of perforations, said grooved member comprising a pair of metal members having recesses 100 in their adjacent faces, a strip of softer material fitted in said recess, said metal members being spaced apart at one side to form a groove of which the strip of softer material forms the bottom.

Signed at the city of Toronto, Canada, 110
this 21st day of February, 1930.
